WALTER P. WATKINS, OF ELIZABETHTOWN, KENTUCKY.

EARTH-AUGER.

1,114,206.

Specification of Letters Patent.

Patented Oct. 20, 1914.

Application filed August 3, 1912. Serial No. 713,159.

To all whom it may concern:

Be it known that we, BENJAMIN G. WATKINS, a citizen of the United States, and a resident of Nehawka, in the county of Cass and State of Nebraska, and TAYLOR WATKINS and WALTER P. WATKINS, citizens of the United States, and residents of Elizabethtown, in the county of Hardin and State of Kentucky, have invented certain new and useful Improvements in Earth-Augers, of which the following is a specification, reference being had to the accompanying drawings.

This invention relates to certain new and useful improvements in earth augers.

One object of the invention is to provide an auger of this character having an improved construction and arrangement of dirt cutting bits whereby the walls or sides of the hole will be cut back from the sides of the auger thereby forming a hole slightly larger than the diameter of the auger which will eliminate unnecessary friction and prevent the accumulation of sticky soil on the outer side of the tool.

Another object is to provide an improved construction and arrangement of dirt lifting blades by means of which fine dirt or sandy soil may readily be removed from the hole.

With these and other objects in view, the invention consists of certain novel features of construction, combination and arrangement of parts as will be more fully described and claimed.

In the accompanying drawings forming a part of this specification and in which like numerals of reference indicate similar parts in the several views:—Figure 1 shows a view partly in section. Fig. 2 is a front view. Fig. 3 is a side view. Fig. 4, is a rear view thereof. Fig. 5, is a cross section of the auger taken on the line 5, 5 of Fig. 2. Fig. 6, is a similar view taken on the line 6, 6 of Fig. 2.

In different localities different kinds of earth augers are necessary. In dry and sandy soils the auger should fit snugly within the hole being drilled and have a large bottom carrying surface. In moist sticky soils the auger should not fit the hole closely, so that it is necessary to provide bits which will cut an opening larger than the diameter of the auger body. Unnecessary friction will result if this is not done.

In the preferred form of our auger, we use a semi-cylindrical body 1 of more than 180 degrees having the straight parallel running edges 9'. The bits are three, comprising the two outer bits 5 and 5', and the intermediately positioned bit 5''. Each bit is cupped or dished, and they are held in staggered position as shown in Fig. 1, the bit 5' being the lowest, the opposite bit 5 coming next, and the intermediate bit 15, being the highest. These bits are arranged in spaced relation as shown in Fig. 6. In addition to being cupped, the edge bits 5 and 5' are bowed outward beyond the surface of the auger body 1, as will be understood in referring to Figs. 1 and 4, so that the hole will have a larger diameter than the auger body 1. As shown in Fig. 5, the bits are pointed. The bit 5 has the outward cutting edge 7, while the opposite similar bit 5', has the inner cutting edge 7'. The edge 22, of the bit, 16, however, corresponds in curvature to the cutting edge 7. The bit 5'' has the straight cutting edge 7 while the opposite edge is curved. In Fig. 1, the bow of the outwardly dished edge bits 5 and 5'' is clearly indicated. A spanner head 3' has its two ends *a* secured to the auger body 1, while its boss 2 is arranged to receive the rod or pipe 3, to which the operating handle 4 is secured. This bit can be successfully and expeditiously employed in drilling holes in clinging soils without danger of the soil clinging to the body of the auger, thereby causing unnecessary friction.

To the upper end of the body 1 is secured a handle socket 2, which is preferably threaded interiorly and forms part of the spanner head 2', the ends of which are riveted or otherwise secured to the body as shown. Secured at its lower end in the socket 2, is a handle 3, on the upper end of which is arranged a cross bar 4, whereby the auger may be readily turned in forming the hole. On the lower end of the semi-cylindrical body 1, between the cutting bits are formed a plurality of shorter lifting blades 6 and 6'. The blades 5 and 6' are substantially V-shaped and are turned to form a scoop shaped bottom or lower end for the same.

One of the edges of the blades 5 is turned outwardly to a slight extent and beveled to form a cutting edge 7, whereby the blades also serve as the bits of the auger. The projection of the beveled cutting edges of the

blades 5, 5', and 5" gradually increases from the lower ends of the blades toward their upper ends and at said upper ends of the beveled edges of the blades which adjoin 5 the smaller blades, are circular notches 8 which facilitate the outward bending or turning of the cutting edges.

By forming the cutting edges of the blades at their upper ends, as shown and 10 described, a hole of slightly larger diameter than the body of the auger will be formed so that the sides of the latter when turned will not engage the walls of the hole, thus 15 eliminating all unnecessary friction and also preventing soft sticky soil from adhering to and accumulating on the sides of the tool. As shown the cutting edge of the central blade 5" is straight and extends obliquely to the axis of the cylindrical body 1. 20 The dished lifting blades 6, and 6', are positioned between the central and edge cutting bits. As shown two smaller lifting blades are located between the bits 5 and 5", while a single cutting bit 6, is located between 25 the cutting bits 5 and 5", these lifting bits being of successively greater length.

By providing the smaller blades 6 between the larger blades the lower end of the auger is closed to a sufficient extent to permit 30 the scooping up and removal of fine dry dirt and sandy soil which is difficult to remove from the holes with the usual form auger.

The purpose and manner of using augers 35 of this character is well known and from the foregoing description taken in connection with the accompanying drawings, the construction and operation of our improved auger will be readily understood, without 40 requiring a more extended explanation.

Various changes in the form, proportion and the minor details of construction may be resorted to without departing from the

principle or sacrificing any of the advantages of the invention as claimed.

Having thus described our said invention, what we claim is:

1. A post hole auger, comprising a body of more than half a cylinder having a centrally positioned and two triangular edge 50 cutting bits arranged in spaced relation each bit being dished outward beyond the circumference of said body, the cutting edge of said central bit being straight and extending obliquely to the axis of said body, 55 a dished lifting blade positioned between one of said edge bits and said central cutting bit, and two smaller lifting blades between the remaining edge bit and central bit said lifting blades being of successively 60 greater length, and a spanner head secured to the upper end of said body, as and for the purpose set forth.

2. A post hole auger comprising a body of more than half the cylinder having a 65 centrally positioned and two triangular edge cutting bits arranged in spaced relation each bit being dished outward beyond the circumference of said body, and a dished lifting blade positioned adjacent said central cutting bit upon both sides, as and for the purpose set forth.

In testimony whereof, we affix our signatures in the presence of witnesses.

BENJAMIN G. WATKINS.
TAYLOR WATKINS.
WALTER P. WATKINS.

Witnesses as to the signature of Benjamin G. Watkins:

CHARLES H. DYSART,
L. R. UPTON.

Witnesses as to the signatures of Taylor Watkins and Walter P. Watkins:

W. H. ROBERTSON,
HORACE HAYS.
